UNITED STATES PATENT OFFICE.

FREDERICK H. SCHROER, OF PHILADELPHIA, PENNSYLVANIA.

TOY.

1,258,151.

Specification of Letters Patent.

Patented Mar. 5, 1918.

Application filed June 15, 1917. Serial No. 174,845.

To all whom it may concern:

Be it known that I, FREDERICK H. SCHROER, a citizen of the United States, residing at Philadelphia, in the county of 5 Philadelphia and State of Pennsylvania, have invented certain new and useful Improvements in Toys, of which the following is a specification.

My invention relates to improvements in 10 toys, the object of the invention being to provide a neat and attractive toy adapted to be operated by a blast of air directed through a tube and causing an ornamental member to revolve.

15 A further object is to provide a toy of the character stated which can be manufactured and sold at a reasonably low price, and it will not only amuse, but also permit a demonstration of lung power.

20 With these and other objects in view the invention consists in certain novel features of construction and combinations and arrangements of parts as will be more fully hereinafter described and pointed out in the 25 claims.

In the accompanying drawings:

Figure 1 is a view in side elevation illustrating my improved toy.

Fig. 2 is an enlarged fragmentary view 30 in longitudinal section.

Fig. 3 is a fragmentary bottom plan view, and

Fig. 4 is a view in section on the line 4—4 of Fig. 3.

35 1 represents a blow tube having a mouth piece 2 at one end, and having a closure 3 at its other end.

A bracket 4 is supported on tube 1, by means of two sleeves 5, 5, located at the 40 respective ends of the bracket and fitting snugly upon the tube. One of these sleeves is made with an integral nozzle 6 projecting at an angle from the sleeve and at its inner end communicating with an opening 7 in the 45 wall of tube 1.

The bracket 4 is provided with a horizontal strengthening brace 8 and this brace 8 is made with a bearing 9 in alignment with a bearing 10 in the center of bracket 4. 50 These bearings 9 and 10 receive a rotary post 11, on which a platform 12 is secured by means of solder 13. The platform 12 rests on the bracket 4 and a head 14 is secured on post 11 below brace 8 so that while 55 the post and platform are permitted a free

rotary movement, they are secured against vertical displacement.

The platform 12 is provided on its lower face with a circular series of blades or vanes 15 against which the nozzle 6 directs the 60 blast of air to impart a rotary movement to the platform and post.

A series of radial arms 16 are secured to the upper portion of post 11, and these arms have eyes 17 at their outer ends supporting 65 hanging bails 18. The bails 18, at their lower ends support miniature air ships 19.

To operate the toy, air is blown through tube 1 and through nozzle 6 against blades or vanes 15. This causes the platform 12, 70 post 11 and arms 16 to revolve. The rotary motion thus created, causes the miniature air ships 19 to swing outwardly as indicated by dotted lines in Fig. 1. The greater the force of air the more nearly a horizontal 75 will the bails 18 assume, and hence the operator can test his lung power, as well as amuse himself by the toy.

By constructing my improved toy as above explained, it will be noted that the 80 bracket 4, with its sleeves 5, and attached parts can be removed from the tube 1, and a rotary device of different design could be substituted.

Various slight changes may be made in 85 the general form and arrangement of parts described without departing from my invention and hence I do not limit myself to the precise details set forth, but consider myself at liberty to make such changes and alterations, as fairly fall within the spirit and scope of the appended claims.

Having fully described my invention, what I claim as new and desire to secure by Letters Patent is:

1. A toy, comprising a blow tube having an opening in its wall, a bracket having sleeves mounted on the tube, one of said sleeves having a nozzle registering with the opening in the tube, and a rotary member supported on the bracket and having blades or vanes adapted to receive the blast from said nozzle.

2. A toy, comprising a blow tube having an opening in its wall, a bracket having 105 sleeves mounted on the tube, one of said sleeves having a nozzle registering with the opening in the tube, a rotary post supported on the bracket, a platform on the post having a circular series of blades or vanes adapt- 110

ed to receive the blast from the nozzle, arms projecting from the post, bails pivotally supported by the outer ends of the arms, and miniature air ships at the lower ends of the 5 bails.

3. A device of the character described, comprising a blow tube having a mouth piece at one end and closed at other end, said tube having an opening in its wall, a 10 bracket having sleeves at its ends mounted on the tube, a nozzle on one of said sleeves communicating with the opening in the tube, a longitudinal brace fixed to the bracket, said brace and bracket having 15 alined bearings, a post mounted to turn in

said bearings, a head on one end of the post against the brace, a platform on the post against the bracket, a circular series of blades or vanes on the platform adapted to receive the blast of air from the nozzle, 20 swinging bails connected to the upper portion of the post, and miniature air ships supported by the free ends of the bails.

In testimony whereof I have signed my name to this specification in the presence of 25 two subscribing witnesses.

FREDERICK H. SCHROER.
